Primary Examiner — Susan Bennett Hattan*Assistant Examiner* — Lauren D McVey(74) *Attorney, Agent, or Firm* — Pillsbury Winthrop Shaw Pittman LLP(57) **CLAIM**

The ornamental design for a shredder, as shown and described.

DESCRIPTION

FIG. 1 is a perspective view of a shredder, showing our new design;
 FIG. 2 is a front view of the shredder of FIG. 1;

FIG. 3 is a back view of the shredder of FIG. 1;

FIG. 4 is a right side view of the shredder of FIG. 1;

FIG. 5 is a left side view of the shredder of FIG. 1;

FIG. 6 is a top view of the shredder of FIG. 1; and,

FIG. 7 is a bottom view of the shredder of FIG. 1.

The broken lines immediately adjacent to the shaded areas and define unshaded regions depict the bounds of the claimed design, while all other broken lines are directed to environment. The broken lines form no part of the claimed design.
